FACE GUARD FOR A HELMET

Fred R. Dunning, Brecksville, Ohio, assignor to Dungard, Inc., Brecksville, Ohio, a corporation of Ohio

Filed Jan. 29, 1965, Ser. No. 83,628

Term of patent 14 years

(Cl. D3—13)

FIG. 1 is a front elevational view of a face guard for a helmet showing my new design;

FIG. 2 is a rear elevational view thereof;

FIG. 3 is a top plan view; and

FIG. 4 is a side elevational view thereof, the broken line showing of a helmet being for purposes of illustration only.

I claim:

The ornamental design for a face guard for a helmet, as shown and described.
